[57] CLAIM

The ornamental design for a shoe bottom, as shown and described.

DESCRIPTION

FIG. 1 is a side elevational view of a shoe bottom showing my new design;

FIG. 2 is a front elevational view thereof;

FIG. 3 is a rear elevational view thereof;

FIG. 4 is an opposite side elevational view of FIG. 1;

FIG. 5 is a top plan view thereof;

FIG. 6 is a bottom plan view thereof;

FIG. 7 is a front elevational view of another embodiment of my new design of FIGS. 1—6;

FIG. 8 is a bottom plan view of the second embodiment shown in FIG. 7, the sides and top of the second embodiment being the same as the first embodiment shown in FIGS. 1, 4 and 5.
